UNITED STATES PATENT OFFICE.

HENRY B. BAKER, OF HULLS, OHIO.

STEAM-BOILER CLEANER.

SPECIFICATION forming part of Letters Patent No. 325,476, dated September 1, 1885.

Application filed June 27, 1885. (No model.)

To all whom it may concern:

Be it known that I, HENRY B. BAKER, a citizen of the United States, residing at Hulls, in the county of Athens and State of Ohio, have 5 invented certain new and useful Improvements in Steam-Boiler Cleaners; and I do declare the following to be a full, clear, and exact description of the invention, such as will enable others skilled in the art to which it appertains to 10 make and use the same, reference being had to the accompanying drawing, and to letters or figures of reference marked thereon, which form a part of this specification.

The figure of the drawing is a representation 15 of vertical sectional view.

My invention has relation to automatic or self-acting water-agitators for steam-boilers and steam-boiler cleaners combined; and it 20 consists in the construction of parts, as will be hereinafter fully described, and particularly pointed out in the claims.

Referring by letter to the accompanying drawing, A designates a steam-boiler, in which the dotted lines X X designate the water-line 25 in boiler. B designates a horizontal pipe extending the entire length of the boiler, near the bottom of the same, and projecting through both heads of the boiler at B' and B'.

C C designate jam-nuts on the pipe B, which 30 are screwed firmly against packing to make the joints tight where the pipe B goes through the boiler-heads and to hold the pipe B firmly to its place. D designates a short curved pipe or joints which enters the top of the 35 boiler at F. A vertical glass sight-tube, G, connects the front projecting end of the pipe B with the short curved pipe D, suitable joints, H H H H, being employed for this purpose.

The end I of the pipe B that projects through 40 the rear end or head of the boiler is provided with a stop cock or valve, J. Intermediate of the boiler-heads the horizontal pipe B is provided with a number of short downwardly-curved tubes or small pipes, K, which connect 45 with the lower side of said pipe B and extend quite near to the bottom of the boiler. The lower ends of said pipes K are reduced one-half in size.

In the rear boiler-head and quite near to 50 the bottom of the boiler I provide a blow-off pipe, L, which is provided with a stop-cock or blow-off valve, M.

The two stop-cocks N and N are only for a convenience to stop or shut off the steam

above and the water below the glass tube G 55 in case of accident in any way to said tube.

The use of the glass sight-tube G is to see when the pipe B is clear of water and the device is at work.

The operation of the invention is as follows: 60 When it is desired to put it in operation, the stop-cock or blow-off valve J is opened and the water is permitted to escape from the horizontal pipe B, and the pipe B will fill with steam from the top of the boiler at F, 65 and then the stop-cock or blow-off valve J is closed. Then from the pipe B the steam will pass into the pipes K to their discharge-points, where it will remain until the cock M has been 70 opened, when the suction on the pipes K, caused by the flow of water through the boiler to the discharge-pipe L, will cause the steam to discharge from said pipes K in the bottom of the 75 boiler, which will aid materially in generating more steam, and at the same time move any sediment or dirt up to the blow-off pipe L, where the dirt or sediment can be blown out through the blow-off pipe L, thereby keeping the boiler clean all the time and aid materially in generating steam; hence a saving of fuel.

The number and the size of the small curved tubes or pipes K may be varied without departing from the character of the invention.

Having thus fully described my invention, 85 what I claim as new, and desire to secure by Letters Patent of the United States, is—

1. The combination, with a steam-boiler having the blow-off pipe with stop cock or valve in one head near the bottom, of the 90 pipe B with curved tubes K and stop cock or valve J, the short pipe D, and the sight-tube G, substantially as specified.

2. The combination, with a steam-boiler having the blow-off with stop cock or valve, 95 of the horizontal pipe B, extending entirely through the boiler and projecting at each end thereof, and provided with small curved pipes K, the short curved pipe D, and the vertical tube connecting the pipes B and D, substantially as specified.

In testimony whereof I affix my signature in presence of two witnesses.

HENRY B. BAKER.
